UNITED STATES PATENT OFFICE.

ELZO B. HUNT, OF HARVARD, ILLINOIS, ASSIGNOR TO HUNT, HELM, FERRIS & COMPANY, OF HARVARD, ILLINOIS, A CORPORATION OF ILLINOIS.

HANGER FOR LITTER-CARRIERS.

1,025,527.

Specification of Letters Patent.

Patented May 7, 1912.

Application filed February 9, 1911. Serial No. 607,492.

To all whom it may concern:

Be it known that I, ELZO B. HUNT, a citizen of the United States, residing at Harvard, in the county of McHenry and State of Illinois, have invented a new and useful Improvement in Hangers for Litter-Carriers, of which the following is a specification.

My invention relates to certain new and useful improvements in hangers for litter-carriers, and is fully described and explained in the specification and shown in the accompanying drawings, in which:

Figure 1 is a side elevation showing my improved device and a portion of a litter-carrier frame to which the same is attached; Fig. 2 is an end view of the same; Fig. 3 is a section on the line 3 of Fig. 2, and Fig. 4 is a top plan of a portion of track showing a curve therein with which the device is particularly adapted to coöperate.

Referring to the drawings, A is a portion of a litter-carrier frame upon which is secured a bracket B. This bracket consists of two side webs b which lie on opposite sides of the frame portion A, and which support between them a central boss b¹ having on its lower face a notch b² diametrically disposed across said face.

C is a roller or grooved wheel adapted to run upon a track D which may be of the flexible rod type. The wheel C is journaled upon a pin at the upper end of a depending member E which extends downward beside the track and underneath the same, having at its lower end a pin E¹ which extends downward through the boss b¹ and terminates in a head e, having on its upper face radial beads e¹ which are adapted to enter the groove b² from the lower face of the boss. The bead and groove are preferably made so that their surfaces fit each other, although this is not absolutely necessary, but the construction is such that under normal conditions the bead, by fitting in the groove, will hold the wheel C exactly in the plane of the track, so that there will be no accidental wobbling or twisting of the hanger upon its pivot upon the frame. It will be understood that such accidental twisting of the hanger upon its pivot is very undesirable because feed and litter-carriers are, in practice, forced out of the barn with a single hard push and run, by reason of the momentum thus acquired, across the barn-

yard to the dumping point, where they are automatically dumped and from which they are automatically returned by reason of the rise of the track when relieved of the load

60 within the carrier.

At many times of the year the barn-yard is not a desirable place to walk in and it is therefore of great importance that a carrier be made so that it can readily be pushed to the dumping point by a single push delivered within the barn. Thus anything which would interfere with the free running of the carrier would be very undesirable because it might cause it to stop before it reached the dumping point or on its return before reaching the barn. Now, any swiveling action between the frame and the hanger of a litter-carrier is most undesirable because it twists the wheel out of the plane of the track with the result that the track 75 grinds on the flanges of the wheel so as to greatly interfere with the momentum of the carrier. The present hanger is of such a type that the roller or wheel is held in perfect alinement at all times so that this grinding does not and cannot occur. On the other hand, it is necessary that, within the barn, where an extra push can readily be imparted by the operator, the hanger should be free to swivel to a considerable extent in 80 passing around curves such as the one shown in Fig. 4. It will be seen that in the present device, while the pulley is yieldingly held in the proper position, it can by the exertion of proper force be turned upon its 85 swivel, the amount of energy required for this purpose being determined by the depth of the groove b² and the bead fitting surface, as well as the amount of material contained in the carrier. With this device, 90 when a curve is reached the track will engage with the flanges of the pulley exerting a twisting pressure upon the swivel and manifestly turning the pulley. As soon as 95 the carrier runs off the curve, the bead and groove will snap into complete registration and the pulley will again be held relatively firm in proper position.

I realize that considerable variation is possible in the details of the construction of the device which I have here set forth as the preferred form of embodying my invention; and I do not therefore intend to limit myself to this specific form, my intention being in the claims hereafter ap- 110

pended to claim all the novel features disclosed in this construction as broadly as the state of the art will permit.

What I claim as new and desire to secure 5 by Letters Patent is—

1. In combination a frame, a bracket rigidly attached thereto, a hanger carrying a roller and swiveled in the bracket, and interfitting parts on hanger and bracket for 10 the purpose set forth.

2. In combination a frame, a bracket rigidly attached thereto, a roller-carrying hanger, a pin thereon passing through a

perforation in the bracket, a head on the pin, and an interfitting projection and depression on the adjacent faces of pin and bracket for the purpose set forth. 15

In testimony whereof I have hereunto set my hand and affixed my seal this 6th day of Feb., 1911.

ELZO B. HUNT. [L. s.]
